UNITED STATES PATENT OFFICE

ALBERT T. SCHEIWER, OF ERIE, PENNSYLVANIA

HAIR-DRESSER'S COMB

Application filed November 28, 1931. Serial No. 577,842.

This invention relates to improvements in combs and pertains particularly to an improved type of comb designed particularly for the use of barbers or hair-dressers.

5 The primary object of the present invention is to provide a comb having teeth of an improved design whereby the engagement of the hair therebetween is facilitated and a hair cutting operation is expedited by the use 10 thereof.

Another object of the invention is to provide a barber's comb of a new and novel design in having a double row of fine teeth arranged in parallel relation and extending in 15 opposite directions from a common back.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark 25 no material departure from the salient features of the invention as expressed in the appended claim.

In the drawing:—

Figure 1 is a view in side elevation of the 30 comb embodying the present invention;

Figure 2 is a sectional view taken on the line 2—2 of Figure 1;

Figure 3 is a view in detail of a portion of the fine teeth of the comb looking toward the 35 ends of the same;

Figure 4 is a detail view similar to Figure 3 but directed toward the ends of the heavy teeth.

Referring now more particularly to the drawing wherein like numerals of reference indicate corresponding parts throughout the several views, the numeral 1 indicates the main back of the comb embodying the present invention which at its inner end is curved 40 inwardly as indicated at 2 toward and merges into the outwardly curved portion 3 of a light weight back 4. The free end of the light weight back 4 joins the pair of oppositely directed relatively heavy terminal teeth 5, while the free end of the main or heavy back 1

joins and terminates in the single heavy terminal tooth 6.

Extending throughout the length of the light weight back 4 of the comb and extending in opposite directions therefrom are the 55 two rows of small or fine teeth 7, the teeth of each row being of substantially the same length. These fine teeth 7 terminate at the transverse center of the comb or at the point where the light back 4 joins the main or 60 heavy back 1 and as shown, the outer side of the heavy back 1 is aligned with the points of the adjacent row of fine teeth 7.

From the opposite side of the heavy back 1 there extends the relatively heavy teeth 8, 65 the ends of which terminate in a line occupying the same plane as the ends of the other row of fine teeth.

As shown in Figures 3 and 4 both the fine and heavy or coarse teeth of the present comb are of circular cross section and the heavy 70 end teeth 5 and 6 are also rounded at their corners. In addition to being circular in cross section each of the fine and coarse teeth are tapered at their free ends to a point somewhat similar to a lead pencil or ordinary 75 straight pin. By forming the teeth in this manner the hair picked up thereby for cutting will spread out more evenly and thus may be cut to present a better appearance 80 than in the use of a comb wherein the teeth have flat opposing faces and sharp corners.

It will also be readily apparent that by forming a comb with a double row of fine teeth as in the present case, the life of the comb is greatly extended, for in the ordinary comb should one or more of the fine teeth become broken it cannot thereafter be used 85 in connection with a hair cutting operation, whereas in the present comb if a tooth or several teeth are broken from one row the comb may be reversed and the other row made use of.

Having thus described the invention, what is claimed is:—

A barber's comb having two transversely divided portions, one of said portions constituting a heavy back and relatively coarse teeth extending from one side thereof, the other of said portions constituting a lighter 100

weight back joined to the heavy back by a curved light intermediate portion and having two rows of oppositely directed teeth extending therefrom and from the said curved portion, the said lighter back being in offset substantially parallel relation with the first back, said comb being of gradually tapering width from the free end of the coarse tooth section to the free end of the fine tooth section, each of said fine and coarse teeth being of circular cross section, and said fine and coarse teeth being all directed transversely of the comb.

In testimony whereof I hereunto affix my
15 signature.

ALBERT T. SCHEIWER.
